VEHICLE DIRECTION INDICATOR

William Edward O'Shei, London, England

Application December 1, 1947, Serial No. 789,097
In Great Britain November 28, 1946

5 Claims. (Cl. 177—329)

1

The present invention relates to vehicle direction indicators of the semaphore type, and more particularly to an improved operating mechanism for locking or holding the arm in its non-displayed position whilst allowing the locking or holding means to release when it is desired to raise the arm manually.

One object of the present invention is to provide an improved flexible lock of the type referred to, which is simple to manufacture and which will release under a relatively small applied force when the semaphore arm is manually raised, whereby the arm will not be unduly strained. Another object is to provide an indicator in which the manual raising of the arm applies a direct force to the actuating armature, in its direction of movement, in the event that the armature should stick and not readily release under the forces applied through the flexible lock.

A still further object of the invention is to provide an indicator in which the arm is locked in the non-displayed position, but in which the lock cannot wedge with such force that it cannot be released by the energisation of the operating solenoid.

In order that the invention may be more clearly understood, reference will now be made to the accompanying drawings, in which

Fig. 1 shows a side view of a vehicle direction indicator according to the invention with some parts cut away to show the operating mechanism more clearly. The mechanism is shown with the arm in the locked position.

Fig. 2 shows a similar view to that shown in Fig. 1 but from the opposite side of the direction indicator.

Fig. 3 shows a view of the mechanism, from the same side as Fig. 2, with the indicator arm in the partly raised position.

Fig. 4 shows a view of the mechanism when the indicator arm is still further raised, as viewed from the same side as the view of Fig. 1.

Fig. 5 shows a sideview of an alternative embodiment with the operating mechanism in the locked position.

Fig. 6 shows a view corresponding to Fig. 5 from the opposite side of the indicator.

Figs. 7 and 8 show views of the mechanism from opposite sides of the indicator, respectively, with the arm in the partly raised position.

Referring to Figs. 1 to 4 of the drawings, 1 is the solenoid and 2 the armature which is slideable therein and is conveniently of circular cross-section. The semaphore arm of the indicator is constructed with a translucent portion 3 which

5 accommodates an illuminating lamp (not shown) and is conveniently constructed as a moulding of translucent plastic material, the inner end thereof being fitted into a socket 4 formed in a metal bearing plate 5 which is pivoted on a spindle 6 extending between the limbs of a U-shaped bracket 7 carried by the back plate 8. The construction of the semaphore arm and its mode of mounting is more fully described in the specification of my co-pending application Serial No. 752,192, filed June 3, 1947.

10 The armature 2 has secured thereto at its upper end a locking plate 9 having an L-shaped slot 10 therein as illustrated. This locking plate 15 may be stamped from sheet metal and be secured by a rivet or spot-welding to the substantially semi-cylindrical end of the armature formed by cutting away part of the material of the armature therat.

20 The bearing plate 5 has pivoted thereto a lever 11 which is conveniently made of channel formed to embrace both surfaces of the end of the bearing plate 5, the pivot pin 12 passing through both walls of the channel and the material of the 25 bearing plate positioned therebetween. A spring 13 coiled around an extension of the pivot pin and engaging with one of its arms 13a above the lever 11 and with its other arm 13b against the pivot pin 6, urges the lever 11 close against the end of the bearing plate.

30 At its free end the lever 11 carries a pin 14 upon which is mounted a grooved roller 15 which is adapted to move within the L-shaped slot 10 formed in the locking plate 9. The pin 14 is also connected by a helical tension spring 16 to a member 17 fixed to and preferably stamped up from the material of the locking plate 9. This spring 16 serves to raise the armature and locking plate 9 when the arm is in the 35 position shown in Figs. 1 and 2, to cause the roller 15 to move in the downwardly extending section of the slot 10 and engage with the inclined inner wedging surface 19 thereof and thus lock the arm in the non-displayed position.

40 When the solenoid 1 is energised to operate the indicator, the armature 2 first moves downwards and extends the spring 16 until the roller 15 lies opposite the horizontal section of the slot 10, whereupon further downward movement of the armature swings the semaphore arm about the pivot 6 to its horizontal position, the roller 15 moving along the horizontal section of the slot 10 during this movement of the arm.

45 When the solenoid 1 is deenergised, the arm falls by gravity, the roller 15 first moving along the horizontal section of the slot 10 to raise the 50

armature 2 until the roller 15 lies opposite the vertical section of the slot 10 when the stretched spring 16 will give the armature a final upward movement to locate the roller 15 in the downwardly extending section of the slot 10 and lock the arm in the non-displayed position.

Whilst the locking mechanism described locks the indicator arm in the non-displayed position to prevent it from swinging out of the case or vehicle body, it nevertheless permits the arm to be raised manually without energising the solenoid, if this should be desired. The action of the flexible lock is as follows.

Upon manually raising the semaphore arm, the lever 11 turns against the action of the spring 13 and the roller 15 rides up the surface 19 of the vertically extending section of the slot 10 (see Fig. 3) and finally snaps into the horizontal section of the slot 10 (see Fig. 4), the spring 13 then moving the lever 11 back close to the end of the bearing plate with consequential slight downward movement of the locking plate 9 and armature 2. Upon further manual raising of the arm, the roller 15 moves across the horizontal section of the slot 10 and lowers the armature.

In order that the arm should not vibrate when held by the lock in its non-displayed position, the lower end of the arm has, in previously known constructions, generally engaged with a buffer or stop of rubber or the like material, and due to the wedging action of the locking means difficulty has been experienced in adjusting the position of this bottom buffer so that the locking means is not so wedged that the solenoid has insufficient power to release the lock when the arm has to be raised electrically. It will be appreciated that if the arm falls with high speed against such a rubber buffer, the lock can tend to move further along the wedge surface when the rubber buffer is compressed, the rebound of the arm then wedging the lock so tightly that the solenoid cannot release it when electric current is applied. Known indicators have therefore generally been adjusted so that the locking member is at the full extent of its possible movement along the wedging surface when the arm is in the non-displayed position, but to make this adjustment accurately and without any play between the end of the arm and the buffer is difficult in mass production.

When the arm is made of more flexible material, such as of polythene as described in the specification of my aforesaid copending application, the rubber buffer may be dispensed with and reliance placed upon the resiliency of the arm, but here again difficulties arise, in mass production, in adjusting the end of the arm relative to a rigid buffer for effecting the locking without vibration and without so wedging the lock that operation under electric power is prevented.

These difficulties are overcome, according to a feature of the present invention, by providing a rigid stop adjacent the upper or pivoted end of the indicator arm, which stop is adapted to engage with a rigid member which is rigidly connected to the arm bearing. In the drawings, this rigid member is constituted by the socket 4 of the metallic bearing plate 5. The rigid stop 18, preferably also of metal, may be carried by or formed integrally with the top bracket for the solenoid 1.

With this construction, the arm is positively held in a definite position when lowered, and the locking roller 15 can engage with any part of the wedging surface 19 of the vertical section of

the slot 10 without wedging the lock to a degree which prevents it being released when the solenoid is energised. The strength exerted by the spring 16 holding the locking member against this wedging surface 19 must, of course, not be made so great as to nullify the advantages of this invention. The momentum of the outer end of the arm, which swings on a larger arc, is absorbed in the arm itself, the rigid stop 18 positively holding the rigid member 4 connected to the arm bearing so that the lock does not wedge.

Whilst, therefore, due to the tolerances necessary in mass production manufacture, the locking roller 15 may engage at different positions along the wedging surface 19, in each position the arm is held against vibration and is not undesirably wedged against actuation by the solenoid.

The stop 18 may, if desired, be made adjustable, for example by making it of strip metal which can be bent to adjust its position relative to the rigid portion 4 of the arm.

If desired, guide members 20 may be carried from the lower end of the indicator framework and be positioned on opposite sides of the lower end of the indicator arm 3 when in its non-displayed position in order to keep it in vertical alignment. The lower end of the arm, however, should not touch any member which would act as a stop or buffer and nullify the effect of the stop at the upper end of the arm.

According to a further feature of the invention, a further stop is provided which is adapted to engage with the rear side of the upper end of the armature (that is the side thereof opposite to the arm) or a member such as the locking plate at said upper end, when the armature is fully projecting from the solenoid and the indicating arm is in the non-displayed position. This stop is preferably made adjustable so that, when in this position, the armature can be positioned substantially centrally with reference to the core tube of the solenoid, thus preventing binding by the armature being wedged against this core tube under the action of the springs or other resilient members holding the arm in the locking position.

This second stop may, as shown in the drawing, comprise a strip of metal 21 which is carried by the framework 8 or the upper bracket 7 of the indicator, and extends forwardly and bears against the rear edge of the locking plate 9. The end of this strip 21 which bears against the locking plate is preferably curved and the position of the stop may be adjusted by simply bending the strip forwards or backwards until the armature 2, when in its upper position, is central with respect to the core tube of the solenoid 1.

Whilst Figs. 1 to 4 show an electrically actuated indicator, it will be understood that new flexible lock according to this invention may be used in conjunction with indicators operated by other sources of power such as by fluid pressure or suction, in which case the solenoid and armature would be replaced by a cylinder and piston.

With the flexible lock described with all previously known constructions, the manual raising of the indicator arm exerts a transverse force upon the armature of the operating solenoid or electromagnet (or the piston rod in the case of a fluid actuated indicator) in order to move it downwards. This causes the armature or the like to bear heavily against the side of the core tube of the solenoid or the back of the framework or case, which is liable to give rise to sticking or binding and resistance to opening, with consequent damage to the indicator arm and mechanism.

unless these parts are made sufficiently strong and heavy to withstand the increased load placed upon them under such circumstances.

A further feature of the invention consists in the provision of means for overcoming this sticking or binding when the semaphore arm is manually raised. To this end, the pivoted member carrying or constituting the semaphore arm is provided with a member, which, upon manually raising the arm from its non-displayed position and the flexible lock failing to release, exerts a force upon the armature or the like in a direction substantially parallel to its normal line of movement, whereby the armature is moved and the flexible lock is released.

In the embodiment illustrated in Figs. 1 to 4, this feature of the invention is attained by providing the bearing plate 5 with a projection 24 which is adapted to lie against or just above the shoulder 25 at the upper end of the armature 2 when the latter is fully raised and is locking the arm in its closed position.

With this arrangement, upon manually raising the semaphore arm this projection 24 bears against the shoulder 25 to move the latter downwardly, if the flexible lock has not previously released the armature. If the armature sticks, the projection 24 moves it downwards with a force acting in its direction of movement, during which time the lever 11 turns and moves the roller 15 up the vertical section of the slot 10 until, after a slight movement, the roller 15 snaps into the horizontal section of the slot 10 and the spring 13 immediately slightly advances the armature, thus moving its shoulder 25 out of engagement with the end of the projection 24. This provides clearance for the said projection, the armature being lowered, upon further manual raising of the arm by the roller 15 moving across the horizontal section of the slot 10.

Figs. 5 to 8 show a modified construction of the locking mechanism in which the lever 11 is dispensed with and the pin 14, which again preferably carries a grooved roller 15, is mounted for movement in a slot 22 cut in the end of the bearing plate 5, a spring 23 (corresponding to the spring 13 of the embodiment shown in Figs. 1 to 4) being provided to urge the pin 14 to the lower end of the slot 22. The slot 22 may be so disposed, for example so that its direction corresponds to the arc about which the end of the lever 11 of the previous embodiment moved, that the pin 14 and roller 15 move in a manner similar to that described above when the flexible lock releases upon the arm being raised manually.

The inner end of the bearing plate may again be provided with a projection 24 for exerting a direct force on the armature in its direction of movement if the latter should stick upon the arm being manually raised. This projection may be so disposed that it only acts positively to move the armature if the flexible lock does not operate and move the armature before the projection engages with the armature.

A still further feature of the invention consists in constructing the locking plate at the top of the armature as a die-casting which is cast integrally with a socket adapted to fit over the end of the armature, the end of the armature being undercut whereby the socket may be compressed therearound or cast therearound to assemble the two parts together. Preferably, the external diameter of the socket portion corresponds approximately to or is less than the diameter of the armature, the end of which may be

reduced in size to fit within the aperture within the socket.

I claim:

1. Vehicle direction indicator comprising a frame member, a semaphore arm, a pivot fixed relative to said frame member about which said semaphore arm is adapted to swing, an actuating mechanism, a locking plate coupled to the actuating mechanism and having an L-shaped slot

10 therein, the first section of the slot extending substantially perpendicular to the direction of movement of the actuating mechanism and the second section extending parallel to said direction, a pin carried by the semaphore arm and

15 engaging in said second section of the slot when the arm is in its non-displayed position, and means permitting said pin to move relative to the semaphore arm and against the action of a spring in a direction, when the arm is in the non-displayed position, away from said second section of the slot.

2. Vehicle direction indicator comprising a frame member, a solenoid carried by said frame member, an armature movable within said sole-

25 noid, a semaphore arm, a pivot fixed relative to said frame member about which said semaphore arm is adapted to swing, a locking plate carried by the armature and having an L-shaped slot therein, the first section of the slot extending substantially perpendicular to the direction of

30 movement of the armature and the second section extending parallel to said direction, a pin carried by the semaphore arm and engaging in said second section of the slot when the arm is in its non-displayed position, means permitting said pin to move relative to the semaphore arm and against the action of a spring in a direction, when the arm is in the non-displayed position, away from said second section of the slot, whereby

35 manual raising of the arm causes said pin to move relative thereto against the action of said spring and to move along said second section until it moves into said first section.

3. Vehicle direction indicator comprising a

45 frame member, a solenoid carried by said frame member, an armature movable within said sole-

40 noid, a semaphore arm, a pivot fixed relative to said frame member about which said semaphore arm is adapted to swing, a locking plate carried by the armature and having an L-shaped slot therein, the first section of the slot extending substantially perpendicular to the direction of

50 movement of the armature and the second section extending parallel to said direction, a pin carried by the semaphore arm, a roller mounted on said pin and engaging in said second section of the slot when the arm is in its non-displayed position, means permitting said pin to move relative to the semaphore arm and against the

55 action of a spring in a direction, when the arm is in the non-displayed position, away from said second section of the slot, whereby manual rais-

60 ing of the arm causes said pin to move relative thereto against the action of said spring and to move the roller along said second section until it moves into said first section, and a sec-

65 ond spring connecting said pin with the locking plate and tending to urge the roller into said second section of the slot.

4. A vehicle direction indicator comprising a semaphore arm, a frame member, a pivot mem-

70 ber carried by the arm and cooperating with the frame member to form a pivot about which the arm is adapted to swing, an actuating member

75 for moving the arm from the non-displayed po-

sition to the displayed position, locking means associated with the actuating member for holding the arm in the non-displayed position, a rigid member which is rigidly connected to the arm pivot, a rigid stop carried by the frame member adjacent the pivot and adapted to engage with the rigid member when the arm is locked in the non-displayed position, and a further stop carried by the frame member which engages with that surface of the end of the actuating member which lies opposite to the arm pivot when the arm is in the non-displayed position.

5. A vehicle direction indicator comprising a frame member, a semaphore arm, a pivot fixed relative to said frame member about which said semaphore arm is adapted to swing, an actuating member movable with respect to said frame member for moving the arm from its non-displayed position to its displayed position, means associated with the actuating member for locking the arm in its non-displayed position, a re-

10

15

20

silient connection between the arm and the actuating member, and a member carried by the arm which, upon the arm being manually raised against the action of the resilient connection, exerts a force upon the actuating member in substantially the same direction that it normally moves to move the actuating member in a direction to release the lock.
